UNITED STATES PATENT OFFICE.

JOHN J. GILROY, OF PITTSTON, PENNSYLVANIA.

AXLE-BOX.

1,136,952.

Specification of Letters Patent. Patented Apr. 27, 1915.

Application filed September 3, 1913. Serial No. 787,965.

To all whom it may concern:

Be it known that I, JOHN J. GILROY, a citizen of the United States, residing at Pittston, in the county of Luzerne and State of Pennsylvania, have invented new and useful Improvements in Axle-Boxes, of which the following is a specification.

The invention relates to a construction of axle box, wherein specific provision is made for delivering the lubricant directly on to the upper surface of the contained axle.

The main object of the present invention is the provision of an axle box in which a lubricant chamber is provided above the bearing block and from which the lubricant is delivered directly on to the block and through suitable channels in the latter to the axle, the construction of the box providing for taking up the surplus oil or lubricant and re-delivering it to the axle.

The invention in its preferred form of details will be described in the following specification, reference being had particularly to the accompanying drawings, in which:—

Figure 1 is a plan of the improved axle box. Fig. 2 is a front elevation of the same. Fig. 3 is a section on line 3—3 of Fig. 1. Fig. 4 is a section on line 4—4 of Fig. 1. Fig. 5 is a plan of the bearing block. Fig. 6 is a front elevation of said block.

Referring particularly to the accompanying drawings, the improved axle box, which aside from the details hereinafter mentioned, may be of any preferred or usual construction, includes what may be generally termed a body 1 open as usual at one side for the introduction of the axle 2, and closed at the opposite side to completely house the free ends of the axle. Centrally of the upper portion of the box, there is formed or provided what may be termed an oil reservoir 3, the same extending transversely through the box being closed at the rear end and open at the front end through comparatively elevated reduced port 4 preferably formed through an enlargement or extension 5 of the box, the port 4 serving as a filling opening and by reason of the overhang of the upper portion of the enlargement, in a measure protected against entrance of foreign matter. A bottom of the lower reservoir immediately adjacent its communication with the port 4 is formed with a pocket

6 adapted to receive packing or the like, whereby to prevent displacement of the oil in the reservoir through jar incident to travel of the car. The bottom wall of the reservoir 3 is formed with an opening 7 through which the lubricant from the reservoir is delivered.

Movably mounted in the box 1 in the usual manner is a bearing block 8, said block in this instance being formed on its upper surface with a comparatively shallow recess 9 to which oil is delivered from the openings 7, the block being formed within the plane of the recess with an opening 10 extending vertically therethrough directly to the axle with radiating channels 11 in communication with the recess and leading therefrom throughout the top and side surface of the block. By this means the oil delivered from the reservoir 3 is directly transferred to the axle and on the upper surface thereof, as will be evident.

The box 1 in both directions beyond the bearing block space is formed to provide packing chambers 12, the forward wall of these chambers being formed with openings through which packing may be introduced. The lower portions of the chambers lead to and terminate adjacent the axle below the lower outer edge of the bearing block, as at 14.

In use the oil from the reservoir finds its way directly on to the top of the axle through the opening 7, the recess 9 in the bearing block and the opening 10 therein, excess oil being taken up by the packing in the chambers 12, finally reaching the bottom of said channels where it is stored or retained and redelivered to the axle for lubrication. The axle box is provided with the usual bolt holes 13.

What is claimed is:—

An axle box formed with an oil reservoir in its upper portion, a bearing block operative within the box and arranged beneath the reservoir, said bearing block having a shallow recess to receive oil from the reservoir, an opening leading from the recess to deliver oil therein to the axle, packing receiving chambers arranged on opposite sides of the bearing block and terminating adjacent the axle, the bearing block having the lateral channels in the upper and side surfaces thereof leading from the recess in said block to the packing chamber, said bear-

ing block having forwardly extending channels communicating with the recess in said block and leading to the axle, the forward wall of the box being formed with packing
5 receiving openings immediately adjacent the axle bearing plane and below normal position of the bearing block.

In testimony whereof I affix my signature in presence of two witnesses.

JOHN J. GILROY.
